SOLE CHAMFERING MACHINE

Wilbur L. MacKenzie, Beverly, Mass., assignor to
United Shoe Machinery Corporation, Flemington, N. J., a corporation of New Jersey

Application December 18, 1942, Serial No. 469,399

7 Claims. (Cl. 69—13)

This invention relates to machines for cementing and chamfering soles which are to be attached to shoes by means of cement. The construction herein disclosed is an improvement upon an arrangement for accomplishing a similar result, which forms the subject-matter of Letters Patent of the United States No. 2,266,127, granted December 16, 1941, upon the application of Walter W. Prue.

When soles are prepared for attachment to shoes by means of cement, the margin of the flesh surface is roughed and a band of cement is applied to this roughed surface extending around the margin of the forepart of the sole. The roughing operation, however, tends to produce an uneven edge portion by reason of the outwardly extending fibers of the leather, especially when the cheaper grades of stock, which are particularly loose-fibered, are employed.

Such an untidy appearance, which would be visible in the completed shoe, is also frequently accentuated by particles of dried cement accumulating upon these fibers. It has therefore been the custom to chamfer the corner of the attaching surface of the roughed sole, thus requiring three separate operations prior to the introduction of the combined chamfering and cementing machine of the Prue patent. This machine, by combining two of the operations constituted a notable improvement and has been successfully employed for simultaneously cementing and chamfering.

However, in the use of such machines, difficulty has been experienced under certain conditions because of the gumming between the gage member and the closely positioned chamfering and hold-down devices, the latter of which regulates and renders uniform the depth of the cut. Furthermore, this machine, like all machines which utilize a drag-knife, required a frequent sharpening of the knife and, sometimes, inexperienced operators inadvertently replaced the knife in the machine in a wrong relation to the associated parts.

Accordingly, the object of the invention is to provide an improved machine for cementing and chamfering in which these difficulties are largely overcome and in which a more rugged construction is provided. One feature of the invention resides in independently pivoted knife and hold-down carriers with the chamfering action of the knife normally controlled by the hold-down.

The problem of maintaining a sharp edge for the knife has been solved in the illustrated construction and in accordance with a feature of the invention by making the knife in the form of a long narrow strip of uniform cross section, one edge of which sharpened before the knife is inserted in the machine, lies beside the hold-down and then providing a holder in which this knife blade is clamped with the greater portion of the

edge on the knife up to the hold-down protected by the clamping means. When such a knife becomes dull, it is only necessary to release the clamp sufficiently to permit the knife to be drawn out, thereby to bring a sharp edge into position for chamfering. Whenever the outwardly-extending used portion becomes long enough to be inconvenient, it may be broken off.

Other difficulties are encountered with a class of soles which are intended for use with Cuban heels and in which the heel-seat portion has been prefitted prior to the cementing of the sole. As a consequence of this heel-seat-fitting operation, shouldered portions are provided at each end of the heel-breast line and the heel-seat portion itself is so radically reduced that the edge of the sole is thin and flexible. If the knife is permitted to ride along such a thin edge, it will catch in the leather and may create a fold ahead of the knife which, when it reaches the shoulder of the heel-breast line, will prevent a continued automatic feeding of the sole and will probably throw the sole out of the machine. This difficulty is avoided in accordance with another feature of the invention by arranging the machine for separate heightwise movements of the hold-down and the knife when chamfering around the heel seat and also for up-and-down movement together as the forepart of the sole is thin or thick. To this end, a separate stop is provided to limit downward movement of the pivoted knife carrier so that the knife may not cut the margin of the reduced heel-seat portion.

These and other features of the invention will best be understood from a consideration of the following specification taken in connection with the accompanying drawings, in which:

Fig. 1 is a side elevation of a part of my improved cementing and chamfering machine, taken from the leaving or rear side;

Fig. 2 is a plan view of the sole-supporting devices and the associated chamfering mechanism and has the position of the overlying work-contacting end of the nozzle and of the upper feed roll indicated in broken lines;

Fig. 3 is a detailed view, taken on the section line III—III of Fig. 4 through the knife carrier and the knife blade;

Fig. 4 is a side elevation of the chamfering and hold-down devices as viewed from the leaving side;

Fig. 5 is a fragmentary elevation of the feed rolls and associated parts;

Fig. 6 is an angular view, on a larger scale, of the end of the hold-down member;

Fig. 7 is an angular view of a portion of a sole which has been cemented and chamfered.

Fig. 8 is a horizontal section on the line VIII—VIII of Fig. 4 but on a larger scale and with the sole-engaging parts in the position which obtains when the heel end of a sole having a prefitted heel seat is passing the knife which is then un-

clamped from the holddown and at that point is not operating on the sole;

Fig. 9 is a side elevation of the holddown and knife, with parts in section and showing these sole-engaging parts in the position which obtains when they are operating on the reduced shank portion of the sole; and

Fig. 10 is a vertical section on the line X—X of Fig. 9.

The invention is illustrated as embodied in a machine of the type shown in Letters Patent of the United States No. 2,073,647, granted March 16, 1937, upon the application of C. A. Newhall. That machine is provided with a tapered upper feed roll 10 having a cylindrical portion 11 (Fig. 5) and with a lower feed roll 12, which rolls grip the margin of a sole S. The rolls, being mounted upon driven shafts contained within arm-like upper and lower supports 14 and 16, move the sole progressively forward to present its margin to the operating tools. The lower support 16 is pivoted at 18 in the machine and may be raised to carry the lower roll 12 into contact with the work by a treadle mechanism not herein shown. On the upper arm 14 is a pivoted carrier 20 for a nozzle 22 to which cement is supplied by way of a pipe 24. The particular nozzle herein illustrated is that covered in my application Serial No. 371,948, filed December 27, 1940, and comprises a series of slidably mounted plates 26 each of which has at its lower end an outlet opening and is spring-pressed toward the work. The position of these outlet openings with respect to adjacent parts of the machine is indicated in dotted lines at 28 in Fig. 2, and a support comprising superposed plates 30 attached to the pivoted arm 20 provides for adjustment of this nozzle around the forward corner thereof which the moving sole is leaving and which is adjacent to the periphery of the sole to produce a band B of cement of uniform width. A stop screw 32 (Fig. 1) limits the downward movement of the nozzle but permits it to be lifted in case of jamming of the work.

As the sole passes beneath the nozzle, it is supported upon the fingers 34 and 36 of a bifurcated plate 38 (Fig. 2) adjustably attached by a screw 40 to a depending bracket which is attached by a screw 42 to the lower roll-carrying arm 16. This plate 38 has a notch 44 to give room for tools to be described. Another work-supporting roll 44 and a table 46 are mounted on an arm 48 (Figs. 1 and 5) pivoted to the arm 16 and held up by a spring 50. The sole, as it is moved forward by the feed rolls 10 and 12, is guided in a path making an acute angle with respect to the axis of rotation of the lower feed roll and hence with respect to the end face of the upper feed roll. This path is determined by a gage member 52, adjustably attached to the supporting plate 38 and providing a contact point 54, and by another gage having a contact point 56 (Fig. 2), this being the forward upright edge 58 on a holddown member 60 (Fig. 6). As a result of this angular relation between the path determined by the gage points 54 and 56 and the direction of movement imparted by the feed wheels, a cross feed is set up which holds the sole in the machine and renders its feeding substantially automatic. Any tendency of the extreme margin of the sole to curl up, because of the lateral pressure set up by the cross feed, is counteracted by downward pressure of the cylindrical portion 11 of the upper feed roll 10 against the upper peripheral corner of the sole.

It has already been pointed out that it is de-

sired to have the depth of the cut C (Fig. 6) substantially uniform, regardless of the variations in the thickness of the sole as successive portions of the periphery thereof are traversed. Accordingly, the holddown 60 and a knife 62 are mounted in carriers 64 and 66, respectively, which are pivoted on a pin 68 which has a screw-driver slot 69 and is carried in the upstanding arms 10 and 12 of a bracket 74 and is threaded in the arm 10 (Fig. 2). This bracket has a tongue-and-groove connection with the lower side of the feed-roll-supporting arm 16, as indicated by the dotted lines 76 in Figs. 1 and 2, and the bracket is secured to that arm by screws 78. It is of such a design that the bearing surfaces of the carriers are well removed from the cement nozzle and are not likely to become gummed thereby.

The holddown carrier 64 has an elongated hub portion 80 surrounding the pin 68 and contacting the arm 10, and the holddown is drawn downwardly with respect to that hub by means of a spring 82 extending between a depending leg 84 (Fig. 4) on the carrier and a threaded rod 86 (Fig. 1) adjustably secured by a thumb nut 88 in a depending arm 90 (Figs. 1 and 2) formed on the bracket 74. The downward movement of the holddown to its idle position is adjustably limited by a stop screw 92 threaded in the bracket 74 and held in adjusted position by a check nut 94. This screw 92 engages the depending leg 84. The left end (Fig. 2) of the hub 80 of the holddown carrier has a reduced portion 96 extending into contact with the arm 12. On this portion 96 there is clamped, for normal operation, a hub 98 of the knife carrier 66. This hub 98 has a split portion 100 (Figs. 1 and 4) in which there is a clamp screw 102 which may be loosened to enable the position of this hub 98 to be adjusted with respect to the hub 80 so that the cutting edge 104 (Figs. 3 and 4) can be brought into the desired relation to the holddown 60 with its overhanging lip 106 which rests upon the upper surface of the sole and acts both to hold it down against the table portion 36 and to determine the depth of cut C by the knife 62. Chips removed by the knife are blown away from the band B of freshly applied cement by air forced through a nozzle 63 (Fig. 1).

The spacing between the knife and the hold-down lip 106 is somewhat critical for best operation because, with different qualities of leather stock, the relation between these parts must be changed to facilitate the escape of chips and to hold the leather for clean, accurate cutting. Accordingly, provision has been made for the adjustment of the knife carrier axially of the pin 68 so that it is possible to regulate this spacing. Hence, the upstanding leg 12 of the supporting bracket is provided with a screw 122 which is locked in adjusted position by a check nut 124, and the end of this screw bears against a depending portion of the knife carrier below its hub 98. Accordingly, the practice is to loosen the check nut 124 and to turn the abutment screw till it contacts the depending part of the knife carrier. Then the clamp screw 102 may be loosened and the abutment screw 122 turned inward, for example, (a fraction of a revolution is usually sufficient), to effect a movement of the hub of the knife carrier along the hub of the holddown carrier to its desired position. The clamp screw 102 is then tightened, whereupon the abutment screw 122 may be backed off to the position shown in Fig. 10 to reduce the friction on the knife carrier.

As previously stated, the knife blade 62 is a straight member of triangular cross section uni-

form along its length. The blade is held in the carrier 66 by a clamp member 108 which is attached by a screw 110 and is recessed at 121 to avoid contact with the edge 104 of the blade. This clamp member has a sloping lower side 123 (Fig. 3) which engages one lateral face of the blade away from the edge 104 and is angularly related to a surface 125 in a recess in the holder 66. This surface 125, which also contacts the lower lateral face of the blade away from its edge, and an abutment surface 126, for the back of the blade, positively determine the position of the knife 62 as well as the angle of cut, and it will be noted that the clamp member 108 extends out (Fig. 2) nearly to the end of the knife blade and therefore protects it against accidental nicking. When the portion which is chamfering the sole becomes dull, however, as it necessarily will in the course of use, it is only necessary to loosen the screw 110 and to move the blade longitudinally to bring a sharp edge portion into use, and ultimately to break off the used portion of the blade. For reasons which will later appear, the knife carrier has a depending member 112 to which is secured a spring 114 the other end of which is attached to an eye-bolt 116 screwed into the lower side of the bracket 74. The lower end of this depending member 112 is widened at 128 (Figs. 3 and 8) to receive both a screw 118 and a screw 120. Of these, the screw 118 is long enough to bear against a portion of the bracket 74 thereby to determine the idle position of the knife carrier while the screw 120 is adapted to rest against the depending leg 84 of the carrier for the holdown.

By virtue of this arrangement, it is possible, when soles of the type mentioned above having prefitted heel-seat portions are to be treated, to loosen the clamp bolt 102 so that the knife carrier may turn about the reduced hub portion 96 of the holdown carrier independently and then, by properly adjusting the screw 118 to prevent the knife carrier, and hence the knife 62, from dropping far enough toward the sole support 36 so that the skived heel-seat portion will ever be acted upon by the knife. The screw 120 will be adjusted to leave a slight space between it and the leg 84 at that time so that the holdown 60 will continue to act on the work. On the other hand, when the shank portions are being treated, the holdown leg 84 will act against screw 120 and hold the knife at a level where it will correctly chamfer these portions and then rise to make a cut C of equal depth in the forepart portion.

In operation, a sole will be presented to the machine and the arm 16 raised to start feeding the sole forward so that its periphery is automatically treated by the chamfering knife which will be guided by the holdown to make a uniform cut C. At the same time, the band B of cement of uniform width will be applied. There is little danger of gumming up the machine since only a small portion of the holdown and of the knife lie alongside and close to each other near the work where cement might be picked up. Further, the bearing surfaces of pin 68 upon which they pivot are remote from the cement-applying nozzle 26. By the clamp screw 102, the knife and holdown may be caused to operate as a unit or separately, as when prefitted soles are to be treated, but their maximum spacing along the edge of the sole in the direction of feeding movement will be limited by the abutment screw 122, and the drag of the work upon the knife will hold it against said screw.

Having thus described my invention, what I

claim as new and desire to secure by Letters Patent of the United States is:

1. In a sole-treating machine of the type having a sole-feeding mechanism, a member having an upright gage surface and also having a hold-down surface overlying the upper surface of the work, said member being pivotally supported for movement heightwise of the sole, and a separately pivoted chamfering tool the position of which heightwise of the sole is controlled by said member, said tool being thereby arranged to remove material to a uniform depth irrespective of the thickness of the sole.
2. In a sole-treating machine of the type having a sole-feeding mechanism, a support, an arm having a holdown overlying the upper surface of the sole pivotally mounted on said support, said arm having a hub portion extending laterally from said arm, and a knife holder provided with a clamping member surrounding said laterally extending portion of the holdown arm to hold them for movement together to the end that the holdown controls the knife.
3. In a sole-treating machine, a support, a plurality of carriers independently pivoted on said support, springs urging said carriers downwardly, stop screws for said carriers adjustable thereby individually to determine the extent of downward movement of the carriers, a holdown in one carrier, and a knife in another carrier.
4. In a sole-treating machine, a support, a plurality of carriers independently pivoted on said support, springs urging said carriers downwardly to idle positions, stop screws between the support and said carriers adjustable thereby individually to limit the downward movement of the carriers with respect to said support, a holdown in one carrier, a knife in another carrier, and means on the knife carrier spaced from the holdown carrier when said carriers are in idle position and operating to cause the holdown to lift the knife carrier after a predetermined movement of the holdown away from the support.
5. In a sole-treating machine of the type having a sole-feeding mechanism, a pivot supported laterally of said feeding mechanism, a holdown member having a hub tiltable on said pivot, a chamfering member having a hub also mounted about said pivot, and means for axially adjusting the hub of said chamfering member with respect to the hub of the holdown member.
6. In a sole-treating machine of the type having a sole-feeding mechanism, a pivot supported laterally of said feeding mechanism, a holdown member having a hub tiltable on said pivot, a chamfering member having a hub also mounted about said pivot, and means for clamping one hub to the other hub in any one of a plurality of angular positions around the pivot.
7. In a sole-treating machine, a support, carriers pivotally mounted on said support, resilient means urging said carriers toward the work, a holdown in one carrier, a knife blade in the other carrier, a stop screw cooperating with the support to determine the extent of movement of the holdown carrier, means on said knife carrier overlapping the holdown carrier so that upward movement of the holdown carrier is communicated to the knife carrier, and an independent stop member cooperating with the support and the knife carrier for limiting the downward movement of the knife carrier irrespective of the movement in that direction of the holdown carrier.

WILBUR L. MACKENZIE.
